United States Patent

Des. 240,563
Patented July 13, 1976

240,563

THIN ABSORBENT PAD FOR A SANITARY NAPKIN OR THE LIKE

Howard A. Whitehead, Appleton, and Ralph V. Braun,
Neenah, Wis., assignors to Kimberly-Clark Corporation,
Neenah, Wis.

Filed Aug. 26, 1974, Ser. No. 500,726

Term of patent 14 years

Int. Cl. D24—04

U.S. Cl. D83—1 A

FIG. 1 is a top plan view of a thin absorbent pad for a sanitary napkin or the like illustrating our new design.
FIG. 2 is a bottom plan view thereof.

FIG. 3 is a section taken on line 3—3 of FIG. 1.

FIG. 4 is a top perspective view thereof with one end turned up to show the bottom side thereof.

We claim:

The ornamental design for a thin absorbent pad for a sanitary napkin or the like, as shown.
